(57) **CLAIM**

The ornamental design for a television apparatus, as shown and described.

DESCRIPTION

1. Television apparatus

1.1 : Front

1.2 : Back

1.3 : Left

1.4 : Right

1.5: Top

1.6: Bottom

1.7 : Perspective

1.8: Enlarged

1.9: Enlarged

1.10: Enlarged

1.1-1.10 are drawings showing an embodiment of the television apparatus. Reproduction 1.8 is an enlarged view of the upper right corner of the back of the television apparatus of reproduction 1.2. Reproduction 1.9 is an enlarged view of the back-middle of the television apparatus of reproduction 1.2. Reproduction 1.10 is an enlarged view of the front lower right corner of the television apparatus of reproduction 1.1.

(Continued)

The present product is used for displaying video and playing audio, and the broken lines form no part of the claimed design.

1 Claim, 10 Drawing Sheets**(58) Field of Classification Search**
